(57) **CLAIM**

The ornamental design for an automotive brake pedal arm, as shown and described.

DESCRIPTION

FIG. 1 is a top perspective view of an automotive brake pedal arm according to our new design;

FIG. 2 is a front view of the automotive brake pedal arm;

FIG. 3 is a back view of the automotive brake pedal arm;

FIG. 4 is a right side view of the automotive brake pedal arm;

FIG. 5 is a left side view of the automotive brake pedal arm;

FIG. 6 is a top view of the automotive brake pedal arm; and,

FIG. 7 is a bottom view of the automotive brake pedal arm. The broken lines illustrate portions of the automotive brake pedal arm that form no part of the claimed design.

1 Claim, 7 Drawing Sheets
